CLAIM

The ornamental design for a pair of footwear soles, as shown and described.

DESCRIPTION

FIG. 1 is a lateral perspective view of the footwear sole for a left foot;

FIG. 2 is a medial perspective view of the footwear sole of FIG. 1;

FIG. 3 is an anterior (front) view of the footwear sole of FIG. 1;

FIG. 4 is a posterior (rear) view of the footwear sole of FIG. 1;

FIG. 5 is a medial view of the footwear sole of FIG. 1;

FIG. 6 is a lateral view of the footwear sole of FIG. 1;

FIG. 7 is a top view of the footwear sole of FIG. 1; and, FIG. 8 is a bottom view of the footwear sole of FIG. 1.

The embodiment of the footwear sole shown in FIGS. 1–8 is for a left foot. The embodiment of the footwear sole for a right foot is a mirror image of the embodiment shown in FIGS. 1–8 about a sagittal plane of a human body.

The portions of the article shown in broken lines form no part of the claimed design.

1 Claim, 8 Drawing Sheets
